UNITED STATES PATENT OFFICE

115,768

DESIGN FOR A DOLL

Mary Cooley Smith, South Weymouth, Mass.

Application May 10, 1939, Serial No. 84,921

Term of patent 7 years

To all whom it may concern:

Be it known that I, Mary Cooley Smith, a citizen of the United States, residing at South Weymouth, in the county of Norfolk and Commonwealth of Massachusetts, have invented a new, original, and ornamental Design for a Doll, of which the following is a specification, reference being had to the accompanying drawing, forming part thereof.

Fig. I is a front view of a doll showing my new design; and

Fig. II is a side view thereof.

I claim:

The ornamental design for a doll, substantially as shown.

MARY COOLEY SMITH.
